[57] CLAIM

The ornamental design for plunge router, as shown and described.

DESCRIPTION

FIG. 1 illustrates a perspective view of a plunge router according to the present invention.

FIG. 2 illustrates a front view of a plunge router according to the present invention.

FIG. 3 illustrates a back view of a plunge router according to the present invention.

FIG. 4 illustrates a side view of a plunge router according to the present invention.

FIG. 5 illustrates another side view of a plunge router according to the present invention.

FIG. 6 illustrates a top view of a plunge router according to the present invention; and,

FIG. 7 illustrates a bottom view of a plunge router according to the present invention.
